UNITED STATES PATENT OFFICE.

HAROLD R. BUTLER, OF NEW YORK, N. Y.

DESIGN FOR A PUZZLE BOARD OR BOX.

SPECIFICATION forming part of Design No. 28,371, dated March 8, 1898.

Application filed January 24, 1898. Serial No. 667,826. Term of patent 7 years.

To all whom it may concern:

Be it known that I, HAROLD R. BUTLER, a citizen of the United States, residing at the city of New York, in the county of New York and State of New York, have invented and produced a new and original Design for Puzzle Boards or Boxes, of which the following is a specification, reference being had to the accompanying drawings, which form a part thereof.

In the drawings, Figure 1 is a top or plan view of a puzzle-board, showing my new design; and Fig. 2 is a vertical transverse sectional view taken on the line $x-x$, Fig. 1.

15 The leading or material feature of my design consists of a rectangular box 1, having a flat or horizontal bottom 2, surrounding vertical side walls 3, and an open top 4, and internally within said rectangular box and between the vertical walls thereof is arranged a flat or horizontal platform 5, from the end of which extends a chute-shaped incline 6, and on top of which is arranged a vertical annular flange or ring 7, having an opening 25 8 in its rear wall. The flat or horizontal in-

terior platform 5 is elevated some distance above the bottom 2 of the box 1 and occupies a large part of the area of said box.

The chute-shaped incline 6 extends downwardly from the bottom platform 5 to the bottom 2 of the box at a central point with respect to the front edge of said platform and is provided with vertical side flanges 9. The vertical annular flange or ring 7 is centrally arranged upon the top surface or area of the platform 5.

Having fully described my invention, I claim as new and desire to secure by Letters Patent—

The design for a puzzle board or box, substantially as herein shown and described.

In testimony that I claim the foregoing as my invention I have signed my name, in presence of the subscribing witnesses, this 22d day of January, 1898.

HAROLD R. BUTLER.
